FIG. 8 is a front perspective view thereof showing a first example state of use;

FIG. 9 is a front perspective view thereof showing a second example state of use;

FIG. 10 is a top perspective view thereof showing a third example state of use;

FIG. 11 is a front perspective view of an armrest for automobile showing our new design according to a second embodiment;

FIG. 12 is a front view thereof;

FIG. 13 is a rear view thereof;

FIG. 14 is a left-side view thereof;

FIG. 15 is a right-side view thereof;

FIG. 16 is a top view thereof;

FIG. 17 is a bottom view thereof;

FIG. 18 is a front perspective view thereof showing a first example state of use;

FIG. 19 is a top perspective view thereof showing a second example state of use;

FIG. 20 is a front perspective view of an armrest for automobile showing our new design according to a third embodiment;

FIG. 21 is a front view thereof;

FIG. 22 is a rear view thereof;

FIG. 23 is a left-side view thereof;

FIG. 24 is a right-side view thereof;

FIG. 25 is a top view thereof;
